(57) **CLAIM**

The ornamental design of a toothbrush holder carrier assembly, as shown and described.

DESCRIPTION

FIG. 1 is an isometric front view of the disposable toothbrush carrier assembly;

FIG. 2 is a top view of the disposable toothbrush carrier assembly;

FIG. 3 is a bottom view of the disposable toothbrush carrier assembly;

FIG. 4 is a front view of the disposable toothbrush carrier assembly;

FIG. 5 is a back view of the disposable toothbrush carrier assembly; and,

FIG. 6 is a side view of the disposable toothbrush carrier assembly.

The broken lines showing of the logo in FIGS. 1 and 4 are for illustrative purposes only and form no part of the claimed design.

1 Claim, 4 Drawing Sheets

FIG. 1

FIG. 2

FIG. 3

FIG. 4

FIG. 5

FIG. 6
